US00D453142S

(12) **United States Design Patent** (10) Patent No.: **US D453,142 S**
Watanabe et al. (45) Date of Patent: ** Jan. 29, 2002

(54) **CIRCUIT BLOCK FOR POWER SUPPLY**

(75) Inventors: **Osamu Watanabe, Hidaka; Junji Kondo, Kawagoe; Toshihiko Kobayashi, Iruma, all of (JP)**

(73) Assignee: **Tamura Corporation, Tokyo (JP)**

(**) Term: **14 Years**

(21) Appl. No.: **29/125,211**

(22) Filed: **Jun. 20, 2000**

(30) **Foreign Application Priority Data**

Apr. 24, 2000 (JP) 12-010685

(51) LOC (7) Cl. **13-01**

(57) **CLAIM**

The ornamental design for a circuit block for power supply, as shown and described.

DESCRIPTION

FIG. 1 is a front perspective view of the circuit block for power supply showing our new design;

FIG. 2 is a front elevational view;

FIG. 3 is a rear elevational view;

FIG. 4 is a top plan view;

FIG. 5 is a bottom plan view; and,

FIG. 6 is a right-side elevational view.

The left-side elevational view is symmetry of the right-side elevational view.
